UNITED STATES PATENT OFFICE

146,708

DESIGN FOR A WOVEN METAL FABRIC OR THE LIKE

Albert J. Fitzgerald, Syracuse, N. Y., assignor to
General Electric Company, a corporation of
New York

Application October 18, 1945, Serial No. 122,937

Term of patent 14 years

(Cl. D54—15)

To all whom it may concern:

Be it known that I, Albert J. Fitzgerald, a citizen of the United States, residing at Syracuse, in the county of Onondaga, State of New York, have invented a new, original, and ornamental Design for a Woven Metal Fabric or the like, of which the following is a specification, reference being had to the accompanying drawing, forming a part thereof.

Fig. 1 of the drawings is a plan view, and Fig. 2 is a sectional view, taken along line 2—2 of Fig. 1, of a woven metal fabric or the like showing my new design.

I claim:

The ornamental design for a woven metal fabric or the like, as shown.

ALBERT J. FITZGERALD.
